UNITED STATES PATENT OFFICE.

RALPH S. POISTER, OF CANTON, OHIO, ASSIGNOR TO UNITED ALLOY STEEL CORPORATION, OF NEW YORK, N. Y., A CORPORATION OF NEW YORK.

INGOT-MOLD BOTTOM PLATE.

Application filed September 1, 1922. Serial No. 585,662.

To all whom it may concern:

Be it known that I, RALPH S. POISTER, a citizen of the United States, and a resident of Canton, in the county of Stark and ⁵ State of Ohio, have invented certain Improvements in Ingot-Mold Bottom Plates, of which the following is a specification.

The invention relates to molds for casting ingots from molten metal, which may ¹⁰ be tapered from a smaller lower section to a larger upper section and are provided with an aperture in the bottom through which the ingot can be detached and driven from the mold; and the object of the improvement ¹⁵ is to provide means for closing the aperture and protecting its rim from the action of the molten metal.

The aperture in the bottom of such a mold has frequently been closed by a metal plate, ²⁰ having its edge portion seated in a recess around the rim of the aperture; and difficulty has been experienced, when molten metal is being poured into the mold, from a portion of the same flowing under one edge ²⁵ of the plate and lifting it from its seat, and not only permitting some of the molten metal to flow downward or into the aperture, but causing the plate to rise, either partly or entirely, into the body of the ³⁰ ingot.

Furthermore, a flow of molten metal into the aperture, not only wears away the rim of the aperture, but forms a fin or stem which makes it difficult to detach and remove the ingot from the mold.

The present invention involves the use of a plate for closing the mouth of the aperture, and a plug attached to the plate for preventing a tilting of the plate, which ⁴⁰ may also be used for detaching the ingot and driving it from the mold.

A preferred form of the invention, and various modifications thereof, are illustrated in the accompanying drawings, forming ⁴⁵ part hereof, in which—

Figure 1 is an elevation section of an ingot mold, showing the improved plate and plug therein;

Fig. 2, an elevation section of a plate in a ⁵⁰ mold for casting the preferred form of the plug;

Fig. 3, a similar view showing the plug cast to the plate;

Fig. 4, a plan section of the same, on line ⁵⁵ 4—4, Fig. 3;

Fig. 5, a detached perspective view of the preferred form of plate and plug; and

Figs. 6 to 15 are fragmentary sections showing modified methods of attaching a ⁶⁰ plate and plug together.

Similar numerals refer to similar parts throughout the drawings.

The mold 16 is open at the upper end ¹⁷ for receiving molten metal and its sides ¹⁸ are preferably tapered downward and inward to a bowl shaped bottom 19 in the center of which is a conically tapered aperture 20, around which aperture the bottom of the bowl is preferably countersunk to form a recess 21 for receiving the edge portions of a plate ⁷⁰ 22.

A conically tapered plug 23 is secured to the plate, whence it may extend downward in contact with the sides of the aperture and preferably protrudes a substantial distance ⁷⁵ below the bottom of the mold.

The attachment of the plug to the plate holds the same flatwise upon its seat around the mouth of the aperture, and prevents a tilting of the plate which would permit the ⁸⁰ molten metal to flow under one edge thereof.

The mold preferably rests upon a table 24 or other support having an opening 25 into which the plug may protrude, and for the purpose of detaching an ingot from the ⁸⁵ mold, the same may be raised and lowered so that the plug will strike upon the table in well known manner; and when the ingot has been removed from the mold, the protruding plug may be broken off from the ⁹⁰ bottom of the ingot by striking it with a hammer or the like.

The preferred way of making an attached plate and plug is to provide a rolled, cast or forged plate 22 with a central aperture 26, and place the same in a mold block 27 countersunk to receive it bodily and provided with a central semi-spherical recess 28; upon which is superposed another mold block 29 having a tapered opening 30 in ¹⁰⁰ which molten iron or steel is poured to form the body of the plug 23 together with a neck

31 extending through the central aperture in the plate, and a head 32 is formed in the recess of the lower mold block, as shown in Fig. 3, thus forming the connected plate and plug, as shown in Figs. 1 and 5.

Figs. 6, 7 and 8 show modified forms of plates and hollow plugs cast integrally together; Fig. 9 shows a hollow plug having a shank riveted in a central aperture in the plate; Fig. 10 shows a similar plate and plug connected by a separate rivet; Fig. 11 shows a plate with a cup shaped plug spot welded thereto; Figs. 12 and 13 show plugs of differential lengths riveted and bolted respectively to a plate; and Figs. 14 and 15 show plugs with wooden pins in their heads secured to a plate by nails; all of which modified forms of plug and plate serve substantially the same purpose as the preferred form illustrated and more fully described.

I claim:

1. A mold having an aperture in its bottom, and a plate seated on the rim of the aperture and having a plug secured thereto fitting into the aperture. 25
2. A mold having an aperture in its bottom with a recess around its rim, a plate seated in the recess, and a plug attached to the plate fitting into the aperture. 30
3. A mold having an aperture in its bottom with a recess around its rim, a plate seated in the recess, and a plug attached to the plate fitting into the aperture, and protruding below the same. 35
4. A mold bottom plate having an aperture therein, and a plug cast upon one side of the plate with a neck extending through the aperture and a head engaging the other side of the plate.

RALPH S. POISTER.
